United States Patent Office

Des. 232,878
Patented Sept. 24, 1974

232,878

CHILD'S TABLE

Jerrold J. Krumholz, West Orange, Herbert H. V.
Reisgen, Westfield, and George C. Kress, Union, N.J., assignors to Kusan, Inc., Nashville, Tenn.

Filed Mar. 30, 1973, Ser. No. 346,665

Term of patent 14 years

Int. Cl. D6—03

U.S. Cl. D6—5

FIG. 4

FIG. 1

FIG3

FIG2

FIG. 1 is a front elevational view of the child's table showing our new design;

FIG. 2 is a side elevational view thereof;

FIG. 3 is a bottom plan view thereof; and

FIG. 4 is a top plan view thereof.

The rear of the table is a mirror image of the table as depicted in FIG. 1.

We claim:

The ornamental design for a child's table, as shown and described.
